Des. 226,693

Patented Apr. 10, 1973

226,693

FLOATING TRAY FOR SOAPS AND LOTIONS OR THE LIKE

Marie R. Harper, 11916 S. Painter Ave.,
Whittier, Calif. 90605

Filed Sept. 29, 1971, Ser. No. 184,978

Term of patent 14 years

Int. Cl. D28—99

U.S. Cl. D86—10 A

FIG. 1 is a perspective view of a floating tray for soaps and lotions or the like showing my new design;

FIG. 2 is a left side elevational view;

FIG. 3 is a front elevational view;

FIG. 4 is a rear elevational view; and

FIG. 5 is a cross sectional view taken on line 5—5 of FIG. 1.

I claim:

The ornamental design for a floating tray for soaps and lotions or the like, as shown and described.
